Patented Mar. 1, 1921.

UNITED STATES PATENT OFFICE.

WILLIAM H. BURSTALL, OF OXNARD, CALIFORNIA, ASSIGNOR OF ONE-HALF TO
EUGENE J. DIEDRICH, OF OXNARD, CALIFORNIA.

TOOL-WRENCH.

1,369,962.

Specification of Letters Patent.

Patented Mar. 1, 1921.

Application filed May 27, 1920. Serial No. 384,572.

To all whom it may concern:
Be it known that I, WILLIAM H. BURSTALL, a citizen of the United States, residing at Oxnard, in the county of Ventura 5 and State of California, have invented a new and useful Tool-Wrench, of which the following is a specification.

This invention relates to tool wrenches and is more particularly directed to tool 10 wrenches adapted for use in connecting and disconnecting tools in wells and designed for use in connection with the standard type of oil well jacks.

The object of the invention is to provide 15 a variable angle tool wrench.

Another object is to provide a wrench having an operating handle which is capable of angular adjustment relative to the tool engaging throat.

20 Another object is to provide means by which the operating force applied to the handle is transmitted to the tool engaging member in opposite directions.

Another object is to provide a wrench in 25 which the entire pull of the handle is transmitted to the free end of the tool engaging member.

Various other objects and advantages will 30 be more fully apparent from the following description of the accompanying drawings, which form a part of this disclosure, and which illustrate a preferred form of embodiment of the invention.

Of the drawings:
35 Figure 1 is a perspective view of a wrench embodying the features of the invention.

Fig. 2 is a top plan view.

Fig. 3 is a side elevation.

40 Fig. 4 is a section on line $\alpha^4-\alpha^4$ of Fig. 2.
Fig. 5 is a plan view illustrating in full lines the usual types of wrench and the method of operation, and showing in dotted lines, the wrench of the present invention.

Wrenches of the general character herein 45 referred to, are primarily used for the purpose of screwing together or unscrewing the threaded joints by which various types of well tools, rods and other elements of well drilling and operating equipment are connected, and are ordinarily operated with one 50 of the standard types of well jacks.

These tools have squared shank portions 55 for engagement by the wrenches, the shank of one tool or rod being engaged by one wrench to keep said tool from turning and

the shank of the adjacent tool or rod being engaged by a second wrench which is operated to screw up or unscrew the joint, one wrench being a left hand wrench and the other a right hand wrench.

In Fig. 5 I have shown the ordinary type of one piece wrench in use, the wrench 1 engaging the shank of the tool which is to be kept from turning and the wrench 2 engaging the tool or rod to be turned. The 60 wrench 1 is shown, engaging an abutment 3 on the circular ratchet track 4 of a well jack and the wrench 2 is shown engaged by the carriage 5 of the jack, the carriage having an operating handle 6 which operates suitable mechanism within the carriage to propel the carriage along the track and operate the wrench 2. This is the ordinary type 65 of well jack and is now so well known in the art as to need no detailed description herein.

In practice it often happens that the faces of the square shanks become longitudinally alined when the joint is tight or just as the final tightening pressure is to be applied, in which case the two wrenches will be relatively positioned approximately 90° apart, as illustrated in Fig. 5.

Under these conditions the movement of the carriage 5 will be in the general direction indicated by the arrow 7, this direction 70 being approximately parallel with the throat of the holding wrench 1 and toward the open end of said throat. Therefore, the holding wrench 1, while preventing a rotation of one tool part or rod, does not prevent a tilting of the string of tools by the force exerted by the jack carriage.

Further it will be pointed out, that the general line of force is directly between the carriage 5 and abutment 3, as indicated by 75 the dotted line 8 and due to this, the resulting tendency will be for the track 4 to buckle outwardly as indicated by the arrow 9.

With the wrench of the present invention 80 the handle thereof may be positioned at various angles relative to the tool engaging throat, thereby eliminating the unfavorable conditions and results above outlined. With reference to Figs. 1 to 4, the wrench as illustrated, comprises a bifurcated shank engaging body or jaw member 10 having a shank receiving throat 11, one end of the body being pivotally connected at 12 to the operating handle 13, the opposed free end having a rounded nose 14 adapted to engage into 85

either of three socket recesses 15 of a tie link 16. These recesses form a series of abutment walls 25 either of which engages the nose 14. Said tie link has a bifurcated inner end engaging over the handle 13 and is pivoted thereto at 17, the bridge member being also provided with a handle 18 to facilitate manipulation thereof.

The body 10 is provided with a bail 19 adapted to be engaged by suitable tackle to support the wrench while applying it to or removing it from the tools, if desired.

By reference to Fig. 5 it will be seen that by engaging the tie link with the free end 15 of the body or jaw member, with the nose 14 engaged into the outer recess 15, the handle 13 will be angled relative to the tool receiving throat 11 to bring the handle closer to the handle of the holding wrench, and that by this relative positioning of the two wrenches, the force applied will more nearly be exerted longitudinally of the track and transversely across the open throat of the holding wrench instead of in a direction parallel to said throat.

With particular reference to Fig. 2 it will be observed that when a force is exerted on the handle in the direction of arrow 20, this force will be distributed to the pivots 12 and 30 17 in opposite directions as indicated by arrows 21 and 22. By the bridge member 16, the pull of the handle is transmitted directly to the free end of the jaw member, the reverse force applied to the pivot 17 coöper-

ating to tend to produce a squeezing together of the two limbs of the jaw member. This serves to prevent a fracturing of the body under heavy strains and permits a much lighter structure for a given size wrench than does the ordinary type of 40 wrench.

It is to be understood that the wrench of the present invention may be made as right or left hand wrenches or that one form adapted for use as either could be designed 45 without departing from the broad scope of the present invention.

I claim—

1. A tool wrench comprising a rigid one piece body having a receiving throat, a handle pivoted at one end to the body, and a link member pivoted on the handle between its ends and having a series of abutments 50 adapted to singly engage the free end of the body.

2. A tool wrench comprising a rigid one piece body having a receiving throat, a handle pivoted at one end to the body, and a link member pivoted on the handle intermediate its ends and provided with a series 60 of recesses for engagement by the free end of the body.

Signed at Oxnard, California, this 20th day of May, 1920.

WILLIAM H. BURSTALL.
